US0D1071097S

(12) **United States Design Patent** (10) **Patent No.:** **US D1,071,097 S**
(45) **Date of Patent:** **** Apr. 15, 2025**

(54) **NOZZLE**

(71) Applicant: **Engineered Controls International, LLC**, Elon, NC (US)

(72) Inventors: **Kevin Jordan**, Gibsonville, NC (US); **Andrew B. Mendenhall**, Mooresville, IN (US); **Paul T. Zink**, Fishers, IN (US)

(73) Assignee: **Engineered Controls International, LLC**, Elon, NC (US)

(**) Term: **15 Years**

(21) Appl. No.: **29/826,417**

(22) Filed: **Feb. 11, 2022**

(51) LOC (15) Cl. **23-01**

(52) U.S. Cl.

USPC **D23/223**

(57) **CLAIM**

The ornamental design for a nozzle, as shown and described.

DESCRIPTION

FIG. 1 is a perspective view of a design for a nozzle.

FIG. 2 is a side view of the design shown in FIG. 1.

FIG. 3 is a side view, opposite that shown in FIG. 2, of the design shown in FIG. 1.

FIG. 4 is a front view of the design shown in FIG. 1.

FIG. 5 is a rear view of the design shown in FIG. 1.

FIG. 6 is a top view of the design shown in FIG. 1.

FIG. 7 is a bottom view of the design shown in FIG. 1; and, FIG. 8 is a detailed view of a portion of the design shown in FIG. 6.

The broken lines illustrate portions of the nozzle that form no part of the claimed design. The dot dash broken lines indicate cutoff boundaries for the enlarged detailed portion view and form no part of the claim.

1 Claim, 8 Drawing Sheets
